UNITED STATES PATENT OFFICE.

CEPHRES R. POMAVILLE, OF DETROIT, MICHIGAN, ASSIGNOR TO THE MICHIGAN STOVE COMPANY, OF DETROIT, MICHIGAN, A CORPORATION OF MICHIGAN.

AIR AND GAS MIXING DEVICE.

1,144,501.

Specification of Letters Patent. Patented June 29, 1915.

Application filed March 4, 1915. Serial No. 12,189.

To all whom it may concern:

Be it known that I, CEPHRES R. POMAVILLE, a citizen of the United States of America, residing at Detroit, in the county of Wayne and State of Michigan, have invented certain new and useful Improvements in Air and Gas Mixing Devices, of which the following is a specification, reference being had therein to the accompanying drawings.

The ovens of gas ranges are entered by an oven door and are heated by gas burners. Such burners have orifices supplying an explosive mixture of gas and air which is ignited at the orifice. If too much or too little air is mixed with the gas the mixture will not ignite or if such mixture is changed while the gas is burning, the flames will be extinguished. The mixture of gas and air is intended to be at the end of the burner farthest from the flame orifices and consists of a gas jet discharging toward the burning end and to provide for the correct amount of air, openings are provided for its admission; the force of the gas jet inducing a current sufficient to draw in the air which is mixed as the gas and air rush through the pipe leading to the flame orifices. As the induced current is changed by variations in gas pressure, adjustable shutters are provided to vary the air mixture until the flame shows proper combustion and until the oven heats properly. Even the proper mixture of gas and air will not burn at the orifices without a secondary supply of air. There is therefore an opening (one or more) to supply such air at the point of combustion. In some ovens the openings are quite large in others quite small.

By opening the oven door quickly a suction is produced which causes a sudden rapid flow of secondary air through the openings provided therefor, and also causes a suction on the burner itself, which pulls in an extra amount of air. If the gas is on full and the air is proportioned properly, the force inside the tube is more than that caused by the oven door opening and will therefore not be influenced. Closing the oven door with a bang produces the contrary effect. The air shutters are set for the maximum gas at full flame and when the flame is turned very low the induced current is very weak and draws in only as much air as is needed but the air mixer openings are

still open. Now if the oven door is opened very suddenly, the secondary air openings cannot supply enough to meet the suction, which causes such a strong pull on the flame orifices, with their very small flames, that an extra quantity of air is drawn in at the open mixer and this excess air extinguishes the flames. When the door is closed very quickly an air pressure is caused in the oven, which extra air cannot go fast enough out of the secondary air openings and therefore is pressed into the flame orifices extinguishing the flames. The user in either case may not notice that there is no flame and as the gas is still on an explosion will shortly occur when the gas reaches a flame in some other part of the stove.

The object of this invention is to open or close the air mixer as the gas is decreased or increased. Thus when the flame is very low the air opening is very nearly closed and when the oven door is opened or closed, the secondary air openings are obliged to take care of the suction or increased air pressure in the oven and cannot pull extra air through the air mixers or push air into the flame orifices. The flame cannot be extinguished however low it is turned.

Another object of this invention is to provide a device wherein the means for controlling the passage of air and the means for controlling the passage of gas to the device are simultaneously operated by a common operating element, and said means are so correlated that when a given quantity of gas passes through the device a given quantity of air will also pass therethrough and as the quantity of air is increased or decreased the quantity of gas will be proportionately increased or decreased.

A further object of this invention is to provide an air and gas mixing device embodying a gas inlet valve having a plug, means movable with the plug of the valve for regulating the admixture of air and gas, and means forming part of the first mentioned means adapted to independently proportion the quantity of air for mixing purposes.

A preferred form of air and gas mixing device will be hereinafter specifically described and then claimed, and reference will now be had to the drawing, wherein—

Figure 1 is a front elevation of a portion of a gas range, partly broken away and

partly in section, illustrating an air and gas mixing device in connection with the burner of a gas heated oven; Fig. 2 is a side elevation of an air and gas mixing device in accordance with this invention; Fig. 3 is an end view of the same showing the gas and air wide open and the regulating shutter half closed; Fig. 4 is a plan of the device; Fig. 5 is a longitudinal sectional view illustrating the shutter construction; Fig. 6 is a detail sectional view of a portion of the shutter, and Figs. 7 to 10 inclusive are dia-grammatic views illustrating the relative positions of shutters and a valve plug.

15 In the drawings, 1 denotes an ordinary gas burner pipe having a bell shaped end 2 providing a mixing chamber 3. The bell shaped end of the pipe has diametrically up-posed inwardly projecting lugs 4. Con-20 nected to said lugs by screws 5 or other fas-tening means is a stationary end plate 6 pro-vided with a concentric opening 7 and a plu-25 rality of equally spaced sector shaped open-ings 8, the latter admitting air to the cham-ber 3. The peripheral edge of the end plates 6 protrudes from the bell shaped end of the burner pipe and constitutes a guide for an outer rotary shutter 9 and an inner rotary shutter 10. The inner rotary shutter 30 10 has a concentric opening 11 registering with the opening 7 of the end plate and open-35 ings 12 corresponding in size and shape to the openings 8 of the end plate and adapt-ed to register therewith.

35 The outer rotary shutter 9 has a concentric opening formed by a sleeve 13 which extends into the openings 11 and 7 and cen-ters the outer shutter relative to the inner shutter and the end plate. The outer shut-40 ter 9 has openings 14 corresponding in size and shape to the openings 12 of the inner shutter 10 and the peripheral edges of the outer shutter terminate in an annular flange 15 surrounding the peripheral edges of the 45 end plate 6 and the inner shutter 10. This peripheral flange has a plurality of prongs or teats 16 which are bent inwardly to mov-ably hold the outer and inner shutters on the end plate 6.

50 The flange 15 of the outer shutter 9 is cut away, as at 17, and the peripheral edge of the inner shutter 10 is provided with an apertured lug 18 which is bent into the plane of the outer shutter 9, as best shown in Fig. 55 6. The cut away portion 17 of the flange provides clearance for the apertured lug 18, and connected to said lug by a screw 19 or other fastening means is a washer or retain-ing member 20 having the edge thereof over-lying the outer shutter 9, to frictionally hold the inner shutter in an adjusted position relative to the outer shutter. An adjust-60 ment of the inner shutter relative to the outer shutter is accomplished by holding the outer shutter and using the lug 18 as a finger

piece for shifting the inner shutter; the re-taining member 20 sliding over the outer shutter within the space defined by the cut away portion 17 of the flange 15. This cut away portion of the flange is of sufficient 70 length to allow the inner and outer shutters to be adjusted whereby they will co-operate in providing air inlet openings, the area of which can be increased or decreased.

Extending through the sleeve 13 of the outer shutter is a nozzle 21 of a gas inlet valve or cock 22, said valve being in com-munication with a suitable supply of gas. The gas inlet valve is of the conventional form with the exception of the plug 23 of 80 said valve, said plug having an end thereof provided with a rigid arm 24 radially dis-posed relative to the plug body. The outer end of the arm 24 terminates in a knob or protuberance 25 between the side walls 26 85 of a channel member 27 secured to the outer shutter 9, contiguous to the flange 15 thereof.

When installing an air and gas mixing device in accordance with this invention, the inner and outer shutters 10 and 9 are ad-justed whereby the openings 12 and 14 thereof completely register. The inner and outer shutters as a unitary structure are shifted whereby the openings thereof will fully register with the openings 8 of the end 95 plate 6 when the gas is turned on full. Holding the outer shutter 9, the inner shutter 10 is now adjusted, if necessary, to de-crease the area of the air inlet openings un-til there is a proper admixture of air and 100 gas to maintain a perfect combustion at a burner 28 in communication with the pipe 1. Adjustment of the shutters as a unitary structure relative to the end plate 6 is some-what similar to adjusting or setting an ordi-nary air mixture until there is a fair com-mingling of air and gas, which can be de-termined by observing the flame at the burner 28. Now, with the inner and outer shutters properly adjusted they are shifted 105 as a unit in synchronism with the movement of the valve plug 23, and as the rotary shutter is moved, it regulates the admission of air to the mixing chamber 3, the quantity of air being in proportion to the quantity 110 of gas.

As further illustrating the action of the gas cock relative to the air control, reference will be had to Figs. 7 to 10 inclusive, show-ing the gas cock plug and the air control 115 in the same plane, while in actual arrange-ment, they are disposed in planes at right angles. When the plug is turned wide open, as in Fig. 7, all of the openings of the air control are wide open, and when the plug is turned a sixteenth of a revolution, as in Fig. 8, the gas is cut down one-half and the air openings are half opened. When the plug is turned an eighth of a revolution, as 120 in Fig. 9, the air openings are closed. Just 125

- as the gas opening of the cock plug is closed or opened, the air openings are closed. The plug will not hold gas in this position. When the cock plug is turned a quarter of a revolution or 45 degrees, as in Fig. 10, the gas is securely cut off and the air openings are wide open. This is caused by it taking a 45 degree turn to close the air openings. The openings for the gas in the plug 23 and for the air in the end plate 6 each extend for forty-five degrees. There are four openings provided for the air and two openings for the gas, which gives four open positions of the air valve and two open positions of the 15 gas valve for a complete revolution of each valve and with the valves restricted to a halfturn by the construction shown, there are one open position of the gas valve and two open positions of the air valve.
- 20 Fig. 1 illustrates the use of the air and gas mixing device, of which there may be more than one, in connection with a stove having a gas heated oven 29 heated by the gas burner 28. It will be observed that the bottom of the oven has an air inlet opening 30, which together with openings in the rear wall of the oven sustains combustion in the oven when the door 31 thereof is closed. When the gas is just opened and therefore a very low flame, or turned down very low, nearly turned off; the air openings are closed, and enough air leaks to supply combustion. Now if the oven door is banged shut or opened suddenly there is pressure enough in the burner to prevent the com-
- pressed air in the oven from overcoming it and forcing the flame back into the burner; or a suction in the oven when the door is opened suddenly from drawing air quickly enough through the leakage openings of the 40 air mixer to change the mixture of gas and air.
- 45 The efficacy of the air and gas mixing device is particularly apparent in connection with a gas stove and while in the drawing there is illustrated a preferred embodiment of my invention it is to be understood that the structural elements are susceptible to such variations and modifications as fall within the scope of the appended claim. 50

What I claim is:

The combination with a mixing chamber having air inlet openings, of shutters movable on said mixing chamber and having air inlet openings adapted to register with the openings of said mixing chamber, means adjustably holding said shutters relative to each other whereby said shutters can be moved as a unit, a gas valve adapted to admit gas to said mixing chamber, and a connection between one of said shutters and the plug of said valve adapted to adjust said shutters as a unit simultaneously with an adjustment of said valve.

In testimony whereof I affix my signature 65 in presence of two witnesses.

CEPHRES R. POMAVILLE.
